(57) **CLAIM**

The ornamental design for an oil container drain, as shown and described.

DESCRIPTION

FIG. 1 is a top perspective view of an oil container drain, showing my new design;

FIG. 2 is a bottom perspective view of the oil container drain of FIG. 1;

FIG. 3 is another top perspective view of the oil container drain of FIG. 1;

FIG. 4 is another bottom perspective view of the oil container drain of FIG. 1;

FIG. 5 is a top plan view of the oil container drain of FIG. 1;

FIG. 6 is a bottom view of the oil container drain of FIG. 1;

FIG. 7 is a side elevational view of the oil container drain of FIG. 1;

FIG. 8 is another side elevational view of the oil container drain of FIG. 1;

FIG. 9 is a front end view of the oil container drain of FIG. 1; and,

FIG. 10 is a rear end view of the oil container drain of FIG. 1.

The broken lines shown in the drawings depict portions of the article and form no part of the claimed design.

1 Claim, 8 Drawing Sheets
